[57] CLAIM

The ornamental design for an automobile radiator cap temperature indicator, as shown and described.

DESCRIPTION

The sole FIGURE is a perspective exploded view of the automobile radiator cap temperature indicator of the present invention, showing my new design.

All side surfaces of the temperature indicator are flat and unornamented, as seen in the drawing. The solid black shading in the drawings is understood to represent color contrast. The broken line showing an automobile radiator and radiator cap is for illustrative purposes only and forms no part of the claimed design.
